UNITED STATES PATENT OFFICE.

MORRIS C. SLOAN, OF CHICAGO, ILLINOIS.

ROTARY TOOTHRUSH.

Application filed March 26, 1921. Serial No. 455,783.

To all whom it may concern:

Be it known that I, MORRIS C. SLOAN, a citizen of the United States, and a resident of the city of Chicago, county of Cook, and State of Illinois, have invented certain new and useful Improvements in Rotary Toothbrushes, of which the following is a specification.

My invention relates to a rotary tooth brush and has for its main object the provision of a rotary brush provided with two bristle bearing members, one adapted to brush the inside and one the outside of the teeth.

Other objects will appear hereinafter.

The invention consists in the combinations and arrangements of parts hereinafter described and claimed.

The invention will be best understood by reference to the accompanying drawings forming a part of this specification, and in which,

Fig. 1 is a side elevational view, partly in section along line 1—1 of Fig. 2;

Fig. 2 is a sectional view taken on line 2—2 of Fig. 1;

Fig. 3 is an end elevation;

Fig. 4 is a sectional view taken on line 4—4 of Fig. 3;

Fig. 5 is a sectional view taken on line 5—5 of Fig. 1, and

Fig. 6 is a sectional view taken on line 6—6 of Fig. 1.

The form of invention illustrated comprises a casing 10 provided with a cover plate 11 fastened thereon by screws 12. A gear wheel 13 is mounted in said casing to rotate with a shaft 14 fastened to said gear by a key 15 or in any similar manner. One end 40 of said shaft is journaled in an extension 16 on the interior of plate 11 and the other end is formed integrally with the operating crank 17 provided with a handle 18. At the upper end of the casing a sleeve 19 is fastened in which a tube 20 is mounted and rotated by the gear wheel 13 which engages teeth 21 on said tube. In each end of said tube a stem 22 is fastened in any convenient manner as by means of a screw and each of said stems carries a series of bristles around its surface as shown in the drawing. The bristles on one stem are longer around the central portion of the stem and the bristles on the other stem are shorter around the central portion and longer around the ends. A curved member or shell 23 is movably mount-

ed upon each end of sleeve 19 by means of a resilient collar 24 clamped firmly on said sleeve, and has the pointed end 25 of stem 22 pivotally resting in a depression formed in the laterally bent end 26 of said shell. A handle 27 is threaded into casing 10.

In use the shell is placed against the lip or gum to protect the same and the exposed bristles placed against the teeth, the brush 65 is then rotated by means of the handle 18 so that the bristles travel from the gums toward the ends of the teeth. The brush with the convex surface is used to clean the teeth from the inside of the mouth and the brush 70 with the concave surface is used to clean the teeth from the outside.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A rotary tooth brush comprising a casing, a member rotatably mounted across the edge of said casing, a brush removably mounted in each end of said member, a wheel mounted in said casing to directly engage and rotate said member, and means to actuate said wheel.

2. A rotary tooth brush comprising a casing, a member rotatably mounted across the edge of said casing, a brush fastened to said member, a gear wheel mounted in said casing to engage and rotate said member, a shell removably mounted on said casing to partly cover said brush, a supporting handle mounted on said casing, and means to actuate said gear wheel.

3. A rotary tooth brush comprising a casing, a tubular member rotatably mounted on said casing, teeth formed by providing spaced openings around said member, a brush fastened to each end of said tubular member, a gear wheel rotatably mounted in said casing in mesh with the teeth on said member, and means to rotate said wheel.

4. A rotary tooth brush comprising a casing, a tubular member rotatably mounted across the edge of said casing, a brush re-

movably mounted in each end of said tubular member, a pivot pin at the free end of each brush, and means to partly cover each brush and protect the mouth, said means engaging the outer ends of said pivot pins.

5. A rotary tooth brush comprising a casing, a sleeve fastened to the edge of said casing, a tubular member rotatably mounted in said sleeve, a brush fastened in each end of said tubular member, and means to rotate said member.

6. A rotary tooth brush comprising a casing, a sleeve fastened to the edge of said casing, a tubular member rotatably mounted in said sleeve, a brush fastened in each end of said tubular member, means to rotate said member, a handle to actuate said means, and a shell removably clamped on each end of said sleeve.

10 7. A device comprising a casing, a sleeve fastened on said casing, a tubular member rotatably mounted in said sleeve, a tooth

brush fastened in each end of said tubular member, and a shell removably clamped on each end of said sleeve, said shell extending 25 over each brush and engaging the outer end thereof.

8. A rotary tooth brush comprising a casing, a sleeve fastened to said casing and provided with a peripheral opening, a member rotatably mounted in said sleeve, teeth on said member, a brush fastened in each end of said member, a gear to engage said teeth through the opening in said sleeve and rotate said member, and means to actuate 30 35 said gear.

In testimony whereof I have signed my name to this specification in the presence of two subscribing witnesses.

MORRIS C. SLOAN.
